(57) **CLAIM**

The ornamental design for a housing for an electrical plug or connector, as shown and described.

DESCRIPTION

FIG. 1 is a top perspective view of a first embodiment of a housing for electrical plug or connector, showing our new design, in a typical usage condition;

FIG. 2 is a bottom perspective view thereof;

FIG. 3 is a back elevational view thereof;

FIG. 4 is a front elevational view thereof;

FIG. 5 is a side view thereof, the opposite side being a mirror-image thereto;

FIG. 6 is a top plan view thereof;

FIG. 7 is a bottom plan view thereof;

FIG. 8 is a top perspective view of a second embodiment of a housing for electrical plug or connector, showing our new design, in a typical usage condition;

FIG. 9 is a bottom perspective view thereof;

FIG. 10 is a rear elevational view thereof;

FIG. 11 is a front elevational view thereof;

FIG. 12 is a side view thereof, the opposite side being a mirror-image thereto;

FIG. 13 is a bottom perspective view of the interior of a housing for electrical plug or connector, shown separately for clarity;

FIG. 14 is a rear elevational view thereof;

FIG. 15 is a front elevational view thereof; and,

FIG. 16 is a side view thereof, the opposite side being a mirror-image thereto.

The broken line portion of the figure drawings is included to show unclaimed subject matter only and forms no part of the claimed design.
